MEDICAMENT APPLICATOR

John M. Wittke, Westfield, and Richard M. Monahon, Basking Ridge, N.J., assignors to Esta Medical Laboratories, Inc., Dover, Del., a corporation of Delaware

Filed Oct. 8, 1962, Ser. No. 72,017

Term of patent 14 years

(Cl. D83—12)

FIG. 1 is a side elevational view of a medicament applicator showing the new design;

FIG. 2 is a plan view thereof looking in the direction of arrow 2 in FIG. 1;

FIG. 3 is a bottom plan view thereof, looking in the direction of arrow 3 in FIG. 1;

FIG. 4 is an end view looking in the direction of arrow 4 in FIG. 1, and

FIG. 5 is an opposite end view looking in the direction of arrow 5 in FIG. 1.

FIG. 6 is a cross-sectional view taken on line 6—6 of FIG. 3.

We claim:

The ornamental design for a medicament applicator, as shown.
